UNITED STATES PATENT OFFICE.

SEYED KHALIL, OF NEWARK, NEW JERSEY.

UMBRELLA.

Application filed December 16, 1927. Serial No. 249,399.

This invention relates to improvements in umbrellas.

One of the objects of this invention is to produce an umbrella which will maintain equilibrium irrespective of the varying air currents pressing against the inner and outer surfaces of the foldable covered frame when it is in unfolded position, and to prevent the air current from compressing or condensing within the inner surface of the foldable covered frame.

Another object of the invention is to provide a construction of umbrella which may be more readily drained and in which the lower portion of the umbrella which frequently rots because of the lodgment of water therein, will be fully drained and dried by aeration when the same is folded.

Another object of the invention is to provide an umbrella with a centrally-located aperture which will be automatically opened by the closing movement of the umbrella and closed by the opening movement thereof and which aperture, when the umbrella is in folded position, will communicate with the interior thereof to furnish drainage and aeration, and when the umbrella is in open position, will be covered and maintained in covered position to keep out rain.

Another object of the invention is to provide an umbrella with a centrally-located air vent and shield therefor which will add to the attractiveness of the umbrella without materially adding to the weight or cost of manufacturing.

Still another object of the invention is to provide an umbrella having an aperture adapted to be automatically opened by the closing movement of the umbrella and to be shielded by the opening movement thereof with a shield provided with air channels adapted to be simultaneously opened by the opening movement of the umbrella.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:

Fig. 1 is a vertical section taken at one side of the rod of an umbrella embodying my invention;

Fig. 2 is an enlarged vertical section of the central portion of the umbrella shown in Fig. 1, the section being taken substantially on the line 2—2 of Fig. 3, looking in the direction of the arrow;

Fig. 3 is a section on the line 3—3 of Fig. 2, looking in the direction of the arrow;

Fig. 4 is a perspective view of the central portion of the umbrella shown in Fig. 1;

Fig. 5 is a section on the line 5—5 of Fig. 2, looking in the direction of the arrow;

Fig. 6 is a section similar to Fig. 2, showing the umbrella in folded position;

Fig. 7 is another section taken substantially on the line 7—7 of Fig. 3, looking in the direction of the arrow;

Fig. 8 is a vertical section similar to Fig. 2 of a modified form of my invention;

Fig. 9 is a section similar to Fig. 8, illustrating in folded position, the modified form of umbrella shown in Fig. 8;

Fig. 10 is a section on the line 10—10 of Fig. 8, looking in the direction of the arrow; and

Fig. 11 is a perspective view of a guiding element employed in my invention.

Referring now to these drawings, which illustrate a preferred embodiment of my invention, 1 is the handle of an umbrella, 2 the rod, 3 the skeleton or frame comprising the cover-stretching ribs 3' and the radial arms 3^a pivoted at one end to the ribs 3' and at the other end to a ferrule 3^b slidably mounted on the rod 2, the ribs 3' being pivoted at their inner ends at 4 at a fixed point on the rod 2 and also being suitably connected at various points to a cover 5. In the claims herewith appended, I have termed the conventional umbrella parts hereinabove described as a "foldable covered frame" and will now proceed to point out my improvements thereto.

The inner ends 4 of the ribs 3' are pivoted on ears 6 preferably spaced from the rod 2 and formed, as shown, at the inner end of a guiding element 7. The other end of said guiding element preferably extends above the foldable covered frame of the umbrella and is provided around the circumference with a series of longitudinal slots or vent-apertures 7' separated by bars 8 which are connected at one end with a collar 9 with which the ears 6 are integrally formed and at the opposite end with an ornamental base piece 10 having a centrally-located socket 11 within which the end of the rod 2 seats and to which it is fastened by the pin 10', said element 7, which is shown in perspective in Fig. 11, being also

held in spaced relationship to the rod 2 by the mounting collar 12 to which it is connected by suitable pins 13 and which mounting collar is connected to the rod 2 by a pin 14.

5 The provision of such rib-pivoting and guiding element 7 spaced, as aforesaid, from the rod 2, provides an opening 19 preferably annular in conformation, surrounding the axis of the rod 2 and communicating from 10 the interior of the umbrella through the slot 7' to the exterior thereof. An opening is thus formed which will vent the space beneath the cover and thus permit the escape of air currents coming under said umbrella 15 so as to release such excessive pressure of air currents as would otherwise act against the under side of the cover to turn it inside out. This venting and release of the force of the air currents will obviously enable a 20 person carrying the umbrella to maintain the same in open, upright position without the unbalancing pressures common to unvented covers, and, therefore, with much less effort than can be done without the release 25 of such excessive air currents.

While the means so far described would release all excess air pressure from the interior of the umbrella, it is apparent that unless the venting apertures be suitably shielded, 30 rain would enter therethrough and in the embodiment shown, would pass down on the rod to the handle of the umbrella and hand of the user. I, therefore, provide means for shielding the venting aperture from the admission of rain while allowing such escape 35 of air, and I have shown two embodiments of my invention including different means for so applying a shield. In each embodiment, I preferably employ shield-operating means 40 which will be operative, upon the opening of the umbrella, to shield the venting aperture and, upon the closing of the umbrella, to open the venting aperture so as to provide an effective draining of the interior of the 45 umbrella cover and of the shield and also to provide a passage for the ventilation or admission of air into the folds of the umbrella when the same is in closed position, thus insuring a speedier and more complete drying of 50 the lower end of the cover and preventing rusting of the ribs and decay or rotting of the fabric thereof.

In the preferred embodiment of my invention, shown in Figs. 1 to 7 and 11, I provide 55 a shield 15 connected at its outer periphery with the main cover 5 of the umbrella in such manner as to provide between each of the ribs, a radial air channel communicating with the vent-aperture 19, and in said preferred embodiment, I preferably provide beneath the shield 15 an enlarged vent-aperture 20 by connecting the annular edge 17 of the cover to the ribs at a point somewhat distant 60 from the pivotal connection thereof with the ears 6.

In the said preferred embodiment of my invention, I provide means for automatically shielding the vent-apertures 7' in the guiding element and simultaneously raising the axial or central portion 15^a of the shield 15 to 70 tighten or stretch the same so as to form or produce on the outer surface of the foldable covered frame a series of effective radial air channels 18 communicating through the apertures 7' and through the openings 19 and 20 to the interior of the foldable covered frame. 75

While the said vent-apertures 7' and 19 or 20 when covered by the shield 15 will substantially release the excess air pressure from 80 the interior of the umbrella toward the exterior without admitting rain, a wet umbrella when folded might cause moisture to run from the exterior surface of the cover 5, through the channels 18 of the shield into 85 the interior of the umbrella through the apertures 19 and 20 and collect upon the rod 2 near the point of junction of the ribs. To prevent such a collection of moisture, I employ the vent-aperture 19 and the slots 7' as 90 a drainage and aeration means and I provide means to unshield the external parts of the said slots 7' automatically upon the folding movement of the umbrella, and to shield the said slots automatically upon the opening 95 movement of the umbrella.

In said preferred embodiment, the automatic shielding and unshielding of the slots 7' is produced by the same means and simultaneously with the raising and with the lowering of the shield 15. As is shown in Figs. 1 to 7, I have provided a series of links 21 pivoted at their outer ends 21' to the ribs 3' and at the opposite ends 21^a pivoted on lugs or ears 22' carried by a ferrule 22 slidable up 100 and down on the bars 8 of the guiding member 7. As illustrated, the central or axial portion 15^a of the shield 15 is mounted between a horizontal flange 22^a and the upper pivoted ends 21^a of the links 21. 110

It will be apparent that, upon the opening of the umbrella in the usual way, the links 21 will cause the ferrule 22 and the annular central or axial portion of the shield 15 to be raised so as to shield the air-vent openings 115 through the slots or vent-openings 7' and annular space 19 and at the same time by stretching the shield will cause a more effective opening of the horizontally-extending radial air channels 18 communicating with 120 such vent-openings.

In Figs. 8 and 9, I have shown another means for automatically raising a shield to close the vent-openings to the interior of the umbrella. In this form I preferably carry the inner end 17' of the main cover into a position close to the guiding element 7 so as to leave only a single vent-opening 19 communicating with the venting openings or slots 7' of a guiding member 7 and I preferably provide a 130

shield 15' which may be substantially similar to the shield 15, except that it may be smaller and has a longer connection at its outer end with the main cover of the umbrella. In this 5 embodiment of my invention, a sliding ferrule 22^b is normally and automatically forced to its upper vent-closing position by the action of a spring 23, having one end pressing against an interior spider 15^c integrally connected with said ferrule 22^b and the other end abutting in relatively stationary or fixed position against the fastening collar 12 of the element 7, said ferrule carrying the annular central portion 15^d of the shield 15' upwardly 10 when the umbrella is opened. When, however, the umbrella is closed, the ferrule, together with said central portion 15^d will be drawn downwardly along the guide element against the pressure of the spring 23 to uncover 15 the vent-openings 7' communicating with the annular vent channel 19, thus enabling free passage of air and moisture through said openings while the umbrella is 20 in closed position.

25 Having described my invention, I claim:—

1. An umbrella embodying, in combination, a foldable covered frame having an aperture therethrough, and shielding means for said aperture movable automatically upon the operative movement of said frame to alternately shield and unshield said aperture. 30
2. An umbrella embodying, in combination, a foldable covered frame having an aperture therethrough, and shielding means for said aperture movable automatically upon the folding movement of said frame to unshield said aperture, and upon the opening movement of said frame to shield said aperture. 35
3. An umbrella embodying, in combination, a foldable covered frame having an aperture therethrough, and shielding means having an axial air channel and radial air channels, and means operable upon the opening and closing movements of said frame to close and open 40 said axial and radial channels alternately. 45
4. An umbrella embodying, in combination, a foldable covered frame having an aperture therethrough, a shield for said aperture, means connected to said frame and operable by the folding and opening movements thereof to automatically actuate said shield upon an opening movement to shield said aperture in the said frame and upon a folding movement to unshield the same. 50

55 5. An umbrella embodying, in combination, a foldable covered frame embodying cover-stretching ribs and means for opening and folding said ribs, said frame having an aperture therethrough, a shield for said aperture having a connection at its outer edge with said frame, and means for automatically actuating said shield upon the opening movement of said frame to shield said aperture and upon the folding movement of said frame to unshield the same, said means comprising

links having a pivotal connection with the cover-stretching ribs and with the shield.

6. An umbrella embodying, in combination, a foldable covered frame, a shield-guiding element having a central connection with said frame and having an axially-disposed aperture therethrough and also having radial apertures communicating with said axial aperture, a shield operable automatically upon the opening and folding movements of said frame to move axially and to shield and unshield said communicating apertures, whereby said communicating aperture is shielded upon the opening movement of the umbrella and has direct unshielded communication with the outer atmosphere when said frame is folded. 70
75

7. An umbrella embodying a foldable covered frame having a vent-aperture adjacent to the axis of the cover, a shielding element arranged above said aperture, and means connected with said frame and operable upon the opening movement of the umbrella for actuating said shielding element to shield said aperture against the ingress of rain and upon the closing movement of the umbrella to uncover said aperture to provide for drainage and aeration of said frame when in folded position. 80
85

8. An umbrella embodying a foldable covered frame having an axially-disposed vent-aperture, a shielding element also having an axially-disposed aperture and means for providing above said frame a series of radially-disposed air-channels communicating when the said frame is in open position with the outer atmosphere above said frame and also with said venting aperture, and means operable automatically to open the axially-disposed aperture in the shield upon the folding movement of said frame and to close said shield aperture upon the opening movement of said frame. 90
95
100
105

9. An umbrella embodying a foldable covered frame having an axially-disposed vent-aperture, a shielding element also having an axially-disposed aperture and means for providing above said frame a series of radially-disposed air-channels communicating when the said frame is in open position with the outer atmosphere above said frame and also with said venting aperture, and means operable automatically upon an operative movement of said frame into one of its positions to close said shield aperture and upon movement in the opposite direction to open the same. 110
115
120

10. An umbrella embodying a foldable covered frame having a vent-aperture adjacent to the axis of the cover, a shielding element arranged above said vent-aperture and means connected with said frame and operable upon the opening movement of the umbrella for raising and stretching said shield to provide radially-disposed air-channels opening com- 125
130

municating at one end with the outer surface of said frame and at the other end with the said venting-aperture; said means being operable automatically to open an axially-disposed aperture in the shield upon the folding movement of said frame and to close said shield aperture upon the opening movement of said frame.

11. An umbrella embodying a foldable covered frame having a vent-aperture adjacent to the axis of the cover, a shielding element arranged above said vent-aperture, means operable automatically to open an axially-disposed aperture in the shielding element upon the folding movement of said frame and to close said shield aperture upon the opening movement of said frame, and comprising links pivoted to the cover ribs and having an operative engagement with the central portion of said shielding element.

12. An umbrella embodying a rod, an element connected at an end of said rod and having an aperture surrounding said rod, and a foldable covered frame having a pivotal connection with said element adjacent to the axis of the umbrella and means for covering and uncovering said aperture in said element.

13. An umbrella embodying a rod, an element connected at an end of said rod, and a foldable covered frame having a pivotal connection with said element adjacent to the axis of the umbrella, said element having an aperture surrounding said rod and extending through said frame, and said element also being provided with vertically-disposed slots communicating with said aperture, and means for covering and uncovering said slots.

14. An umbrella embodying, in combination, a foldable covered frame having an aperture therethrough, a vertically-disposed guiding element provided with an interior chamber and having apertures at one end communicating with the interior of said frame and at the side with the exterior of said frame, a shielding element movable verti-

cally on said guiding element to shield and unshield the side apertures which are above said frame upon the opening and folding movement of the umbrella.

15. An umbrella embodying, in combination, a foldable covered frame having an aperture therethrough, a vertically-disposed guiding element provided with an interior chamber and having apertures at one end communicating with the interior of said frame and at the side with the exterior of said frame, a shielding element movable vertically on said guiding element to shield and unshield the side apertures which are above said frame upon the opening and folding movement of the umbrella, said shielding element having radially-disposed air channels communicating with the apertures in said guiding element above said frame and being provided with an axial opening closable automatically upon the opening movement of said frame.

16. An umbrella embodying, in combination, a foldable covered frame having an aperture therethrough, a vertically-disposed guiding element provided with an interior chamber and having apertures at one end communicating with the interior of said frame and at the side with the exterior of said frame, a shielding element movable vertically on said guiding element to shield and unshield the side apertures which are above said frame upon the opening and folding movement of the umbrella, said shielding element having radially-disposed air channels communicating with the apertures in said guiding element above said frame and being provided with an axial opening closable automatically upon the opening movement of said frame, said aperture being upon the folding movement of said frame opened to aerate the folded umbrella.

In witness whereof, I have signed by name to the foregoing specification.

SEYED KHALIL.
